Patented Apr. 24, 1917.

UNITED STATES PATENT OFFICE.

MELVILLE E. PETERS, GEORGE H. FATH, AND ALBERT F. MILLER, OF DENVER,
COLORADO.

BLANK AND LABEL FEEDING ROLLER FOR BLANK-GUMMING MACHINES.

1,223,517.

Specification of Letters Patent. Patented Apr. 24, 1917.

Application filed December 22, 1915. Serial No. 68,271.

To all whom it may concern:

Be it known that we, MELVILLE E. PETERS, GEORGE H. FATH, and ALBERT F. MILLER, citizens of the United States of America, residing in the city and county of Denver and State of Colorado, have invented a new and useful Blank and Label Feeding Roller for Blank-Gumming Machines, of which the following is a specification.

10 Our invention relates to an improved blank and label feeding roller for blank gumming machines; and is designed as an improvement over a feed roller illustrated and described in a pending application for 15 a pneumatically controlled and automatically operating blank gumming and tempering machine, filed May 25, 1915, Serial No. 30,471.

The objects of our invention are:

20 First, to provide a feed roll for blank gumming machines having a removable blank receiving pad, one end of which is adapted to be clamped to said roll, while the other end is engaged by a tension device.

25 Further, to provide a feed roller for blank gumming machines having a longitudinal air passage and air suction apertures leading therefrom through the periphery of the roll, said roll having a supporting shaft also 30 provided with an air passage connected at one end with the passage in the roll and adapted to be connected at its other end with an air pump, said roll being surrounded by a blank receiving pad of suitable 35 material which is clamped at one end to the cylinder while its other end is secured to a rotatable pawl and ratchet controlled tension shaft, said pad having apertures registering with the suction apertures in the 40 periphery of the roll.

We attain these objects by the mechanism illustrated in the accompanying drawings, in which:

Figure 1, is a perspective view of a feed roll constructed and equipped in accordance with our invention.

Fig. 2, is a longitudinal sectional view thereof, showing the air passage and suction apertures.

50 Fig. 3, is an end view showing the pawl and ratchet mechanism for controlling the pad tension shaft.

Fig. 4, is a sectional view on the line 4—4 of Fig. 3.

Fig. 5, is a plan view of a blank-receiving pad. And

Fig. 6, is a plan view of a box covering blank.

Similar letters of reference refer to similar parts throughout the several views.

Referring to the drawings,—

The numeral 1 designates a feed roller embodying our invention.

Our present invention is an improvement over the feed roller illustrated in the above mentioned pending application, and is constructed and operates as follows:

The blanks or labels 2 are fed to the feed roller one at a time, by an automatic blank feeding mechanism which we do not illustrate herewith, and the feed roller receives them on a raised blanket or pad 3, that is cut out at its sides adjacent to its forwardly advancing rotating end to exactly the same outline and size as the advancing feeding end of each blank or label, and the feed roller grips the blank or label and holds it by an air suction force and feeds it to and delivers it to the gumming cylinder and while there are a number of ways of carrying this feature of our invention into effect, we preferably construct and arrange this new feed roller as follows:

The roller 1 is preferably hollow and has a circumferential shell and end flanges 4 and 85 shaft supporting hubs 5 one at each end. This roller is provided with a gap 6 in its circumference, which extends entirely across it from end to end parallel with its longitudinal axis. This gap is formed in the surface of the roller and along one edge of it a row of air suction inlet apertures 7 are formed that extend down into its surface and register with a passage 8, that is formed in the feed roller shell, and which extends longitudinally across it from end to end. The entrance ends of this air reservoir are plugged up and a radially aligned air reservoir aperture 9, is bored down through one end flange 4 of the roller into the axial center of the shaft. The entrance of this aperture at the surface of the roller is also plugged up. Consequently this leaves a closed air reservoir passageway connecting the air inlet aperture with the axial center 105 of the shaft, and an axial aperture 10 is bored in the adjacent end of the shaft until it intersects the radial reservoir aperture

9. This apertured end of the shaft is provided with a suitable thimble to which one end of a pipe 11 is connected, the opposite end of which extends to and is adapted to be connected to an air pump that is secured on the base plate of the machine. This pump may be actuated by a cam which is mounted on a shaft, and a rock arm which is provided with a roller that engages the cam. This 10 rock arm is mounted on a shaft and its free end is connected to the piston rod of the pump. We do not however illustrate the pipe member, the hose or air pump or its cam actuated mechanism above mentioned, 15 but they can be seen in our pending application for a patent filed May 25, 1915, Serial No. 30471 for blank and label feeding and gumming rollers and cylinder for blank and label gumming machines. The row of air 20 inlet apertures forms the blank receiving station of the feed roller, and the feed roller is positioned so that this row of air suction inlet apertures stands at its top and at the center of its vertical plane, and this vertical 25 position of the roller and its air suction inlet apertures we term its blank receiving station, and the roller stops and is held stationary in this position or at this station long enough to receive a blank which is fed to it 30 by an automatic blank feeding mechanism. Consequently this feed roller is an intermittently rotating blank feeding roller. We do not however illustrate the mechanism that intermittently rotates our feed roller or that 35 co-operatively connects it with the blank gumming mechanism of blank gumming machines, as such mechanism is illustrated in our above mentioned applications. It is necessary that the feed roller come to a stop 40 to receive each blank from the blank feeding mechanism, which is so positioned that the advancing edge of each blank is deposited by it directly on top of and over the longitudinally formed row of air inlet apertures. 45 Consequently when this row of air inlet air suction apertures is standing in a vertical plane, the roller stops and this row of air suction inlet apertures becomes its blank receiving station, and when the roller is standing at 50 its blank receiving station the gap is positioned to the right of its row of air suction inlet apertures and close to them, and the side of the gap adjacent to the air inlet apertures slopes inwardly with a flat stepped surface 55 far enough to receive a clamping strip 12 which is removably secured to it by cap screws 13. The edge of this clamping strip is provided with a downwardly projecting bead 14 which fits into a groove 14^A formed 60 in and across the flat surface of the gap. A round spindle 15, is rotatively mounted in this gap one of its ends being mounted in a lug 16 formed on one end of the roll, while its opposite end is mounted in a bushing 17, 65 secured in the adjacent end of the roll. The

center of this spindle is provided with a longitudinal and diametrical slot 18, which is made wide enough to receive one end of a blanket. This blanket comprises preferably a piece of parchment paper, although any other suitable material may be used, and it is cut out in the form shown in Fig. 5. The edge of one end of it is recessed to allow it to fit loosely around the cap screws, and against the shoulder 19 and its other end is 75 narrowed so that it will readily enter the slot 18 in the spindle. The body of this blanket is of the full width of the blank or label, and it is made long enough to extend entirely around the feed roller and to allow 80 its end to be placed under the strip and against its shouldered step, and be clamped in the groove 14^A by the bead 14 of the strip. Then the slack is taken up and the blanket is 85 tightened by turning the spindle, which is especially mounted to stretch the blanket pad around the feed roller and to secure it in a tightened or stretched condition, and to enable this to be done we provide one end of the spindle with a square wrench receiving shank 20, which projects through the adjacent side flange 4 far enough to permit a wrench to be applied to it to turn the spindle. On the opposite end of the spindle we 90 mount a ratchet wheel 21, which is engaged by a spring controlled pawl 22 which is arranged to engage the teeth of the ratchet wheel, and to hold it and the spindle roll and the parchment blanket in adjusted positions. The ratchet wheel supporting end 95 of the stem is preferably mounted in a bushing 17 which is secured to the adjacent end of the roller by screws 23. The stem is rotatably mounted in the bushing, and the ratchet wheel is secured to the terminal end 100 of the shaft, which projects beyond the bushing and the adjacent end of the roller. This pawl 22 is pivotally mounted on the feed roller and its actuating spring 24 is also secured to the feed roller and is arranged to 105 permit the pawl to be moved out of engagement with the ratchet wheel, and release a parchment blanket pad, when it is desired to do so, and to replace a used pad with a new one. Each one of these parchment 110 blanket pads is provided with a row of apertures 25 through it adjacent to its edge portion, which are positioned at a sufficient distance from its clamping edge portion to enable them to register over the air suction inlet apertures 7 of the feed roller, when the adjacent end is clamped to the feed roller by the strip 12. This parchment blanket is 115 adapted to form a raised cushioning pad member for the blanks to rest on, and the air inlet apertures form blank gripping air suction force gripping impulse points that grip the edge of each blank to the pad. These blanket pads are provided in ample 120 quantities to the operators of the feed rollers 130

as they have to be replaced by new ones occasionally, but each pad is cut away from the surface of the feed roller until it is of the exact size of the blank that is to be gummed 5 as to its sides and its front end.

In Fig. 6 we illustrate a plan view of a pasteboard box covering blank 2, and in Fig. 5 we illustrate a plan view of the blanket pad showing in dotted lines what 10 its shape would be when its sides at its front end are cut away to the size and shape of the box covering blank, except as to its length. We have stated that they are preferably mounted on and stretched on the 15 roller before being cut to the size and shape of the blank, but if desired a blank may be laid on them and its outlines marked on the pad and the pad may be cut out before they are placed and stretched on the feed roller.

20 We have illustrated but five air suction inlet apertures in the blanket pad and roller, but more or less can be used if desired. The blanket illustrated is made for a medium sized blank. Consequently larger blanks 25 would require wider blankets and smaller blankets would require narrower blankets, the blankets being made of the exact width of the blanks to be fed by the feed roller to the blank gumming mechanism, and the blankets 30 for all sizes of blanks have to have their sides at their forwardly feeding or advancing ends and only at their forwardly feeding end cut away to the exact size of the blanks, the object of the blanket being to 35 raise the blanks above the surface of the feed roller so as to prevent any adhesive gum from getting onto the surface of the feed roller, and in case any adhesive gum should get on the blanket it can be detected 40 by the operator before it creeps onto the blanket underneath the blank, and when so detected the operator instantly stops the machine and removes the blankets and puts on a clean one. It is necessary to keep the 45 blankets free from the adhesive gum with which the blanks are coated after our feed roller feeds them to the gumming mechanism, as if even a little gum gets on the blanket it is transmitted to the under side 50 of the blank from that which is to be coated by the gumming mechanism, and it causes the blank to stick not only to such parts of the mechanism as it comes in contact with but also to everything it comes in contact 55 with.

Our present blank supporting blanket effectually prevents the gum from getting on the under side of the blanks, as it can be frequently and very quickly removed and replaced by a new blanket, while our air suction blank gripping and holding mechanism is positive and reliable in its action, and permits blanks to be fed very rapidly to the blank gumming mechanism.

60 Having described our invention, what we

claim as new and desire to secure by Letters Patent, is:

1. A blank feeding roller having a surrounding blank supporting blanket of the same shape as the advancing end or feeding 70 end of said blank, means for removably and renewably securing said blanket to said roller, and means including air suction inlet apertures in said blanket and roller for gripping said blank to said roller by an air 75 suction force.

2. A blank feeding roller having a blank supporting blanket removably secured thereto, and means including air suction inlet apertures through said blanket into said 80 roller for gripping and holding a blank to said blanket.

3. A blank feeding roller arranged to receive blanks or labels, a blank receiving and supporting blanket or pad removably and 85 renewably mounted on and secured on said roller, means including a plurality of air suction blank gripping air inlet apertures arranged through said blank into said roller, and means including an air passageway in 90 said roller connecting with said air inlet apertures for producing a blank gripping air suction force at the entrance to said air suction inlet apertures.

4. A blank feeding roller arranged to receive blanks or labels, a blank receiving and supporting blanket or pad removably and renewably mounted on and secured on said roller, means including a plurality of air suction blank gripping air inlet apertures 100 through said blank into said roller, and means including an air passageway in said roller connecting with said air inlet apertures for producing a blank gripping air suction force at the entrance to said air 105 suction inlet apertures, said blanket being clamped at its advancing end portion adjacent to its air inlet apertures to register exactly with the sides of the advancing end portion of the blanks.

5. A blank feeding roller adapted to receive blanks or labels, a blank receiving and supporting blanket or pad removably and renewably mounted on and secured on said roller, means including a plurality of air suction blank gripping air inlet apertures arranged at said blank receiving station of 115 said roller through said blank into said roller, and means including an air passageway in said roller connecting with said air inlet apertures for producing a blank gripping air suction force at the entrance to said air 120 suction inlet apertures, said blanket being provided for said roller of the same width as the greatest width of said blanks 125 and then cut to register exactly with the sides of the advancing feeding end of said blank when registering on said roller at its blank receiving station.

6. The combination in a blank or label 130

1 feeding member, of a roller provided with a removable and renewable blank supporting blanket form of pad of parchment paper or other suitable material, said pad being provided with blank gripping air suction inlet apertures extending into said roller, and means including an air passage in said roller for producing a blank gripping and holding air suction force at the air inlet apertures of said pad.

10 7. A blank feeding roller having a blank or label supporting blanket, means for removably and renewably securing said blanket on said roller, said blanket being of the same shape as the feeding forward end of said blank or label, and means including air suction inlet apertures in said blanket and roller for gripping and holding said blanks to said roller.

20 8. A blank feeding roller having a surrounding blanket supporting blanks of the same shape as the advancing end or feeding in end of said blank, and means for removably and renewably securing said blanket to said roller, and air suction inlet apertures through said pad into said feed roller.

30 9. A blank feeding roller having a surrounding blanket supporting blanks of the same shape as the advancing end or feeding in end of said blank, and means for removably and renewably securing said blanket to said roller, air suction inlet apertures through said pad into said feed roller, said blanket pad being cut away at the sides of its rotary advancing end to fit the sides of the front end of said blank when said blank is properly fed to said air suction blank gripping apertures.

35 10. A blank feeding roller provided with a peripheral gap, a shoulder in said gap, a clamping strip secured along the side of said shoulder by adjustable screws, a blank supporting pad surrounding said roller and

having one end adapted to be placed under said clamping strip and having its adjacent edge arranged to fit around said screws and abut against said shoulder, a groove along said gap over which said blank extends, and a bead on said clamping strip arranged to clamp said blanket in said groove, and means 50 for stretching said blanket around and for securing its opposite end to said roller.

11. In a blank feeding roller for blank gumming machines, the combination of a hollow cylinder provided with a gap, a 55 winding stem provided with a longitudinal slot mounted in said gap, said stem and roller being provided with a spring actuated pawl holding ratchet wheel mechanism, a clamping strip in said gap adjacent 60 to said winding stem, and a blanket of parchment paper or other suitable material fastened at one end to said roller by said clamping strip and having its opposite end arranged and adapted to be inserted in said 65 stem's longitudinal slot, means for rotating said stem and locking it by said pawl whereby said blanket is stretched around said feed roller and is removably and renewably secured thereto, said blanket and roller being 70 provided with a longitudinal row of blank gripping and holding air inlet apertures registering with each other and positioned adjacent to said clamping strip, and means including an air passageway in said roller 75 connected with said air inlet apertures for creating an air suction force in said air inlet apertures.

In testimony whereof we affix our signatures in presence of two witnesses.
